(57) **CLAIM**

The ornamental design for a linear LED light, as shown and described.

DESCRIPTION

FIG. 1 is a top view of a linear LED light, showing our new design;

FIG. 2 is a bottom view thereof;

FIG. 3 is a right view thereof;

FIG. 4 is a left view thereof;

FIG. 5 is a front side view thereof;

FIG. 6 is a back side view thereof;

FIG. 7 is a bottom perspective thereof; and,

FIG. 8 is a top perspective view thereof.

1 Claim, 4 Drawing SheetsFIG. 1

FIG. 2

FIG. 3

FIG. 4

FIG. 5

FIG. 6

FIG. 7

FIG. 8
